HAT

Marianne Tuteur, New York, N. Y., assignor to
Talon, Inc., a corporation of Pennsylvania

Application April 5, 1952, Serial No. 19,201

Term of patent 3½ years

(Cl. D3—13)

To all whom it may concern:

Be it known that I, Marianne Tuteur, a citizen of the United States, residing at New York, in the county and State of New York, have invented a new, original, and ornamental Design for a Hat, of which the following is a specification, reference being had to the accompanying drawings forming a part thereof.

In the drawing:

Fig. 1 is a side perspective view of a hat showing my new design;

Fig. 2 is a similar view thereof as it appears with the flap turned up;

Fig. 3 is a side elevational view of the right side of the hat shown in Fig. 1;

Fig. 4 is a side elevational view of the hat as shown in Fig. 2; and

Fig. 5 is a side elevational view of the left side of the hat as shown in Figs. 1 and 3.

I claim:

The ornamental design for a hat, substantially as shown.

MARIANNE TUTEUR.
